UNITED STATES PATENT OFFICE.

MAX BOOKSTABER, OF PATERSON, NEW JERSEY.

DISPLAY DEVICE.

1,176,270.

Specification of Letters Patent. Patented Mar. 21, 1916.

Application filed March 18, 1913. Serial No. 755,081.

To all whom it may concern:

Be it known that I, MAX BOOKSTABER, a citizen of the United States, and a resident of Paterson, in the county of Passaic and State of New Jersey, have invented certain new and useful Improvements in Display Devices, of which the following is a specification.

The invention relates to display devices and more especially to portable, motor driven devices.

Objects of the invention in part are to provide a novel device of the kind indicated which shall in a superior manner meet the requirements of actual use in the display and handling of merchandise and like things; to provide a novel motor driven, self contained device, which is compact, strong, and capable of carrying heavy loads, and which will operate in a satisfactory manner when the loads or displayed articles are unevenly distributed as to weight; to provide further a device of the kind described which is portable, and which may be easily taken down and set up, and which is complete and integral as it rests upon its own base, and which will permit of ready movement of the merchandise supporting parts independently of the movement derived from the motor in order that any particular merchandise may be quickly reached by a salesman. These and other objects of invention will in part appear hereinafter and will in part be obvious herefrom.

The invention consists in the novel parts, constructions, arrangements, improvements and combinations herein shown and described.

The accompanying drawings, referred to herein and forming a part hereof, illustrate one embodiment of the invention, the same serving in connection with the description herein to explain the principles of the invention.

Of the drawings: Figure 1 is an elevation of a display device constructed in accordance with the principles of the invention; Fig. 2 is a vertical section on the central line of Fig. 1 of the upper part thereof; Fig. 3 is a vertical section; Fig. 4 is a plan of base 50 with top removed; and Fig. 5 is a detail of the cap 33.

Referring to the accompanying drawings, which illustrate by way of example one embodiment of the invention, a display rack is provided having a relatively heavy base and having the standard which supports the

merchandise carrying instrumentalities projecting upwardly from said base and preferably arranged centrally or concentrically therewith. In accordance with one feature 60 of the invention the motor is mounted within said base and is preferably inclosed thereby to protect it against injury, accumulation of dirt and dust or from other injuries.

In the embodied form the base 1 constitutes such a closure having a bottom part 2 and side walls 3 preferably integral therewith. In a practical form of construction intended for use with heavy loads especially, this base may be a casting. As embodied 70 the base is shown of substantially cylindrical form, which conduces to compactness and also to ease of handling and gives also a neat and pleasing appearance which is likewise of great value in devices of this kind. 75 The top of the base 1 in the embodied form serves also as a closure thereto, and consists of a plate 4 fitting over the top of the base and removably secured thereto by suitable means such as the screws 5.

Within the base is the motor 6, the details of certain parts thereof not being necessarily described herein. The motor frame or casing comprises strong plates 7 and 8 which plates are firmly secured to the casting 1 by suitable means such as screws 9. The driving shaft for the display device is indicated by numeral 10 and is journaled in the horizontal plates 7 and 8. Said shaft 10 is vertically arranged and its lower end has a firm bearing 11 in the bottom plate 2 of the motor casing. Thus not only is a firm support provided for the end thrust on the shaft 10 due to the load carried, but the firmly united casing for the motor 95 through the plates 7 and 8 keep the shaft 10 in vertical alinement. The pinion 12 on the shaft meshes with gears 13 and 14 which serve as driving connections from the motor. So far as concerns many features of the invention other suitable and convenient forms of driving connections may be employed.

The supporting and rotating means for the merchandise carrying support comprise 105 a shaft driven from the shaft 10 and supporting and alining means for the upper end of the shaft that are detachably connected to the base 1 so as to insure permanent alinement for the shaft whatever the 110 inequalities in the distribution of the merchandise displayed as to the position and

weight thereof and also the parts are so constructed and arranged as to prevent bending out of alinement or other damage thereto. In connection with this feature of the invention there is likewise provided a construction and arrangement of parts which lend themselves to the decorative and ornamental appearance of the whole, whereby the display device supplements and augments the attractive appearance of the merchandise thereon. The said parts also are readily disassembled and serve also as a closure against foreign substances working into the casing.

15 Referring in detail to the embodied form of means a shaft 15 extends upwardly from the shaft 10 and has a bearing surface 16 resting upon a corresponding surface 17 of the shaft 10. Means for keeping the two 20 shafts in alinement are provided and as embodied comprise a pin and socket connection 18, the pin projecting from the upper surface of the part 17 and the corresponding socket being formed in the shaft 15.

25 An upwardly extending member firmly fixed to the base, and preferably to the cover 4 thereof, so as to be held firmly in position is provided for the purpose of protecting and retaining in alinement the shaft 15. In 30 accordance with certain principles of the invention and usually preferably in actual construction this member is a pipe or tube 19 having a suitable bearing for the shaft 15 in its upper end. The bearing as embodied is a disk 20 which closes the end of the tube 19 and having a central aperture at 21 in which the shaft 15 rotates. The tube 19 will be of rigid material, and is firmly connected to the base while being 40 easily detachable therefrom. As embodied a central boss 22 is provided in the top of the plate 4 and centrally thereof, which boss is provided with an internal thread. The lower end of the tube 19 is correspondingly 45 threaded and screwed into the tapped boss 22, as shown at 23.

50 Means are provided whereby the merchandise supports may be located at different levels in connection with devices such as have been described. In the embodied form a tube 25 is provided encircling the tube 19, although so far as concerns certain features of the invention the member 25 might be of other form. At its upper end the 55 tube 25 is provided with a top 26, integral therewith or inserted therein and connections are provided between the top 26 and the shaft 15. As embodied the shaft 15 is provided with a diminished squared and 60 shouldered portion 27 which fits into a correspondingly shaped aperture in the top 26. Thus the tube or supporting member 25 is carried by the shaft 15 and rotates therewith.

65 At its lower end the member 25 is pro-

vided with a bearing upon the alining member 15 so that it may run easily thereon and uneven side pressure due to irregular distribution of weight in the merchandise displayed may be avoided and negatived as much as possible. As embodied there is provided at the lower end of the tube or member 25 an annular holder 28, provided with a series of balls rolling freely on the surface of the tube 15.

75 The form of merchandise supporting and displaying means comprises a shelf 30, of glass or other suitable material, which may be adjustably supported by the part 25, by suitable means such as the flanged rings 31 80 which may be secured in position by suitable means, such as set screws 32 upon the member 25. Also if desired a suitable ornamental top 33 may be provided for the upper end of the part 25 and this may if desired have suitable merchandise supports, such as the supports 34, attached thereto.

85 Suitable means are provided for preventing backward rotation of the shaft 10, so as to preserve the motor from injury. While 90 the frictional bearing at the surfaces 16—17 will enable the platform 30, or other merchandise support to be rotated by hand in either direction when it is desired to take an article therefrom without waiting for 95 the support 30 to finish its rotation with the shaft 10, and at the same time the other and coöperating parts operate as described to preserve the parts in alinement.

100 Suitable openings and connections, such as 35 and 36, respectively, may be provided for winding the motor and for starting or stopping as desired. The reciprocating rods 35 are pivoted to arms 37 having pawls which actuate ratchet wheels 38 to wind the motor 105 springs.

110 It will be seen that the embodied form realizes the objects of invention and the advantages herein set forth, together with other objects and advantages of great value 110 in a device of this kind.

115 It will be understood further that variations may be made from the illustrated and described structure within the scope of the accompanying claims without departing from the principles of the invention and without sacrificing its chief advantages.

120 What I do claim as my invention and desire to secure by Letters Patent, is:

1. In a display device including in combination a supporting base comprising a casing, a motor inclosed within said casing, a stationary hollow member firmly fixed to said casing and extending upwardly therefrom, a shaft connected to said motor and extending upwardly within said hollow member, said hollow member having a bearing at its upper end for said shaft, a merchandise supporting and displaying means connected to said shaft and extending down- 130

wardly about the said hollow member, and a bearing between said supporting and displaying means and said hollow member near the bottom end thereof.

- 5 2. In a display device including in combination a supporting base comprising a casing, a motor inclosed within said casing, a stationary hollow member fixed to said casing and extending upwardly therefrom, a shaft connected to said motor and extending upwardly within said hollow member and beyond the upper end thereof, a bearing carried by said hollow member for the upper end of the shaft, an outer tube disposed

around said inner tube and connected at its 15 upper end to said shaft, article supporting devices carried by said outer tube, and a bearing between the lower end of said outer tube and said hollow member, said bearing being disposed adjacent said base. 20

In testimony whereof, I have signed my name to this specification, in the presence of two subscribing witnesses.

MAX BOOKSTABER.
